UNITED STATES PATENT OFFICE

DANIEL H. CHASON, OF ELIZABETH, NEW JERSEY, ASSIGNOR TO THE SINGER MANUFACTURING COMPANY, OF ELIZABETH, NEW JERSEY, A CORPORATION OF NEW JERSEY

DISAPPEARING MACHINE REST FOR SEWING-MACHINE TABLES

Application filed June 12, 1928. Serial No. 284,872.

This invention relates to sewing machine tables, more particularly of the drop-head type having a plural-sectioned flush cover for closing the opening in the table-top through which the sewing machine is dropped when not in use. In the manufacture of tables of this type it is customary to make the table-top and cover-sections from the same piece of wood to maintain uniformity of color and continuity of the graining; the piece which is sawed from the table-top in cutting the aperture therein being used for the cover which, in turn, is sawed into a plurality of sections subsequently hinged together, so that the section or sections of the cover not used when the sewing machine is raised to operative position may be swung to a concealed position below the table-top.

It is customary to use one of the cover-sections to support one edge of the sewing machine bed when the sewing machine is raised to operative position and, for this purpose, the practice is to rabbet or undercut the edge of the machine-bed supporting section and glue a strip of wood in the cut-out portion; the glued-in strip projecting beyond the edge of the cover-section to form a machine-bed supporting ledge. The adjacent cover-section is rabbeted to receive such ledge when the sections of the cover are swung to lie in a common plane. These wood-working operations are troublesome and costly.

According to the present improvement no wood-working operations other than sawing straight through the cover, to section the latter, are necessary. The machine-bed supporting section of the cover is provided with one or more disappearing machine rests in the form of metal slides received in suitable guideways screwed to the cover-section. The rests are backed by springs which project them beyond the edge of the cover-section to machine-supporting position when the adjacent cover-section is swung to concealed position. When the adjacent cover-section is swung back to initial position, its edge engages the rests and pushes them back of the edge of their supporting cover-section.

In the accompanying drawings, Fig. 1 is a top plan view of a sewing machine table em-

bodying the invention. Fig. 2 is a transverse vertical section through the table with the sewing machine head in concealed position. Fig. 3 is a similar view with the sewing machine head raised to operative position. Fig. 4 is an edge view of the cover-section which carries the machine-bed supporting rests. Fig. 5 is a detail sectional view through two adjoining cover-sections showing one of the machine bed rests, and Fig. 6 is a disassembled perspective view of the machine-bed rest shown in Fig. 5.

In the preferred embodiment of the invention illustrated 1 represents the top of a sewing machine table having an aperture 2 to the edge 3 of which is connected by hinges 4 the bed 5 of the sewing machine 6 which may be swung about the hinges 4 to raise and lower it through the aperture 3 between the concealed position shown in Fig. 2 and the operative position shown in Fig. 3.

When the sewing machine 6 is in lowered position, the aperture 2 is closed by a flush cover comprising three sections 7^a, 7^b and 7^c; the sections 7^a and 7^b being connected together by the hinges 8 and the sections 7^b and 7^c being connected by the hinges 9. The cover, as a whole, is connected by hinges 10 to the edge of the aperture 3 opposite the edge to which the sewing machine hinges 4 are secured. The cover-sections 7^a, 7^b, 7^c are sawed from the same piece of wood which is cut out of the table-top 1 in sawing the aperture 3, thus maintaining uniformity of color and continuity of the graining of the exposed wood surface.

Let into recesses 11 in the edge of the cover-section 7^a adjoining the section 7^b are a pair of disappearing machine-bed rests 12 in the form of Z-shaped elements, the lower horizontal bars 13 of which are slidably mounted in ways formed by the superposed flat and troughed plates, 14 and 15, respectively. A stop-pin 16 carried by the bar 13 of each rest 12 enters a slot 17 in its supporting troughed plate 15 and limits the sliding movement of the rest. An expansion spring 18 in each recess 11 bears against the upper end of the inclined bar 19, Fig. 5, of each rest and yielding urges the rest to move outwardly from

its recess 11 across the edge of its supporting cover-section 7^a to machine-bed supporting position, Fig. 3, in which position the cover-sections 7^b and 7^c are swung under the section 7^a to a concealed position below the top 1.

When the sewing machine 6 is lowered through the aperture 2, the cover-sections 7^b and 7^c are to be swung about their respective hinge-connections so as to lie in a common plane flush with the table-top, as shown in Fig. 2. During this swinging movement of the cover-sections, the edge of section 7^b adjacent section 7^c engages the machine-bed rests 12 and forces them back into their recesses 11, as shown in Figs. 5 and 2. Wear-plates 20 are preferably secured to the cover-section 7^b to engage the rests 12.

It will be noted that the hinge-pins 21, Fig. 1, of the hinge-connections 8 are back from the abutting edges of the sections 7^a, 7^b. This enables the faces of the wear-plates 20 to engage the rests, as shown in Fig. 5, without a harsh cramping action.

Having thus set forth the nature of the invention, what I claim herein is:—

1. A sewing machine table having a top formed with an aperture and a cavity below said top into which the sewing machine is dropped through said aperture when not in use, a flush cover comprising a plurality of sections hinged together and to the table-top and adapted to close said aperture, and means carried by one of said cover-sections at the hinged joint between it and an adjacent cover-section for supporting one edge of the machine-bed when the machine is raised to operative position, said means being movable relative to its carrier cover-section into and out of machine supporting position.

2. A sewing machine table having a top formed with an aperture and a cavity below said top into which the sewing machine is dropped through said aperture when not in use, a flush cover comprising a plurality of sections hinged together and to the table-top and adapted to close said aperture, and means carried by one of said cover-sections for supporting one edge of the machine-bed when the machine is raised to operative position, said means being automatically movable relative to its carrier cover-section into and out of machine supporting position by engagement with the adjacent cover-section.

3. A sewing machine-table having a top formed with an aperture, a sewing machine having a bed hinged to said top at one side of said aperture to swing through the latter, a flush cover hinged to said top at the opposite side of said aperture, said cover comprising a plurality of sections hinged together, and a spring-pressed machine-bed rest carried by one of said cover-sections adjacent an edge of the latter and pressing against the adjacent edge of the adjoining cover-section, so as to be automatically projectable across said

first-mentioned edge to machine-bed supporting position when said cover-sections are swung relatively to one another about their hinge-connection.

4. In a sewing machine-table, the combination with a plurality of cover-sections having their abutting edges hinged together, of a spring-pressed sewing machine bed-support let into one of said edges and engaging the other edge under spring-pressure and automatically projectable from said one of said edges when the cover-sections are relatively swung about their hinge connection.

5. In a sewing machine-table, the combination with a pair of hinge-connected cover-sections of a machine-bed rest, including a lower horizontal bar having at one end an offset head, the lower horizontal bar of said rest being slidably mounted on the under side of one of said cover-sections and the offset head being received in a notch in one edge of said cover-section, and a spring for urging said rest into engagement with the edge of the adjoining cover-section, whereby when the adjoining cover-section is swung about its hinge-connection the head of the machine-bed rest is projected out of said notch by its spring.

In testimony whereof, I have signed my name to this specification.

DANIEL H. CHASON.
